(57) **CLAIM**

The ornamental design for a toy gun, as shown and described.

DESCRIPTION

FIG. 1 is a right, top, rear perspective view of the toy gun of the instant invention;

FIG. 2 is a left, front perspective view thereof;

FIG. 3 is a right side elevation view thereof;

FIG. 4 is a left side elevation view thereof;

FIG. 5 is a front view thereof;

FIG. 6 is a rear view thereof;

FIG. 7 is a top view thereof;

FIG. 8 is a bottom view thereof;

FIG. 9 is an alternate position view in right, top, rear perspective view; and,

FIG. 10 is a left side view thereof.

The characteristic feature of the design resides in the fact that the toy gun simulates a banana.

The dashed broken lines shown represent portions of a toy gun and form no part of the claimed design.
